UNITED STATES PATENT OFFICE.

WILLIAM McCONWAY, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

CAR COUPLING.

1,404,872.

Specification of Letters Patent. Patented Jan. 31, 1922.

Application filed July 26, 1920. Serial No. 399,131.

To all whom it may concern:

Be it known that I, WILLIAM McCONWAY, Jr., a citizen of the United States, residing at Pittsburgh, in the county of Allegheny and State of Pennsylvania, have invented certain new and useful Improvements in Car Couplings; and I do hereby declare the following to be a full, clear, and exact description of the invention, such as will enable others skilled in the art to which it appertains to make and use the same.

My invention relates to car couplers, and although applicable to couplers for railway cars generally, is especially suitable for couplers for passenger cars in that means are provided for allowing the coupler to swing laterally when the car is passing over curved track and for returning it to a centralized position in the longitudinal axis 20 of the car. The principal object of the invention is to provide an improved device of the character indicated which is strong, durable, efficient, of compact form, easily assembled and repaired, and in which looseness of parts of the mechanism resulting from long continued service is substantially eliminated.

Generally stated, this object is accomplished by mounting upon the stem of the car coupler a centering mechanism comprising a plurality of spring seats or spring boxes which are reciprocatingly mounted upon the stem of the coupler so as normally to project outwardly beyond its sides and to engage a suitable stationary part of the car, the said spring seats being yieldingly separated by a plurality of horizontally spaced parallel springs which are compressible upon a lateral movement of the coupler stem to either side of its central position, and being provided with means for maintaining the springs in spaced relation and also being provided at their outer ends with convex exterior faces allowing the springs to apply balancing or compensating pressure to the spring seats opposing the tendency of the latter to twist when the coupler moves lengthwise in the operations of draft and buffing.

50 In the drawings illustrating the preferred embodiment of the invention,—

Figure 1 is a plan view of a car coupler embodying the invention, the parts being in

normal position and a portion of the car being diagrammatically illustrated.

55

Fig. 2 is a side elevation of the mechanism.

Fig. 3 is a view, partly in plan and partly in horizontal section, illustrating the relations assumed by the parts when the coupler 60 swings laterally to an extreme position of displacement.

Fig. 4 is a detail view partly in elevation and partly in vertical section.

Fig. 5 is a detail horizontal section of one 65 of the reciprocating spring seats or spring boxes.

The general features of construction of the car coupler in which my invention is embodied may be and preferably are of the 70 character disclosed in Patent No. 1,311,699 granted to William Kelso July 29, 1919, although it will be appreciated that the present invention is applicable to car couplers having details of construction unlike those 75 which are the subject of that patent.

In the drawings, 1 indicates the head and 2 is the stem of a car coupler, these parts, if desired, being pivotally connected by means of a pivot pin 3 in a well known manner. The coupler is designed to be mounted upon the car so as to swing laterally with respect thereto, and for that purpose the rear end of the coupler stem may be provided with suitable pivot pin apertures 4 which 80 are adapted to receive a tail pin for connecting the coupler to the draft yoke (not shown).

Where, as illustrated in the drawings, the coupler is provided with a head 1 which is 90 pivotally attached to the coupler stem, it is preferred to centralize the head with respect to the stem by means of a centering slide or frame 5 which is adapted, when the coupler head turns upon the pivot pin 3, to 95 be forced rearwardly on the coupler stem 2 so as to effect a compression of the spring 6 that is interposed between said stem and the centering slide. The construction and mode of operation of the sliding frame 5 are 100 well known and are described in the Kelso patent heretofore mentioned.

The coupler stem is open through its sides so as to permit spring seats or spring boxes 7 to project outwardly beyond the sides of 105 the stem. Where the reciprocating slide 5

- for centering the coupler head is employed the lateral openings through the coupler stem are made of sufficient length to permit the requisite longitudinal movements of said 5 slide, and the spring seats 7 may be mounted on the slide 5 and project through suitable openings therein, the reciprocating movements of said spring seats in a direction transversely of the coupler stem being dictated 10 by guiding surfaces upon the slidable frame 5 after the manner of the construction disclosed in the Kelso patent heretofore referred to. The openings through the sides of the coupler stem may conveniently 15 be formed by fashioning the forward portion of said stem with a plurality of vertically spaced parallel bars or arms 8 which engage the upper and lower faces of the centering slide 5.
- 20 The spring seats 7 are yieldingly separated by a plurality of transversely extending springs 9 which are compressible upon a lateral movement of the coupler stem to either side of its central position.
- 25 In the normal or centralized position of the coupler the springs 9 maintain the spring seats 7 in their projected positions so that the outer ends of the latter engage the neighboring vertical faces 10 of stationary 30 parts of the car. Each of the spring seats 7 is preferably provided on its interior with a wall or web 11 which extends between the parallel horizontally spaced springs 9 so as to maintain them in spaced relation; and at 35 its outer end each of the spring seats is preferably formed with a convex exterior face 12 which extends on opposite sides of the neighboring partition or web 11. By arranging the springs 9 in horizontally spaced 40 twin relation between the spring seats 7, which are elongated lengthwise of the car, the tendency of the said seats to twist and develop looseness resulting from the frictional drag of their outer ends against the 45 stationary parts of the car when the coupler executes draft and buffing movements is resisted and substantially eliminated; and this advantageous result, consequent upon 50 affording spring support for the spring seats practically throughout their entire length, is augmented by reason of the convex form of the ends of the spring seats which enables the pressure of the springs 9 to have a balancing effect tending to maintain 55 the spring boxes in proper alinement with each other. The increased length of the spring seats 7 resulting from the parallel arrangement of the springs 9 is not detrimental, but is in fact advantageous in that 60 the spring seats or spring boxes may be made of increased strength rendering it practically impossible for them to be sheared or broken off should they be pulled or pushed beyond the edge of the carrier iron 13 when
- the coupler stem is displaced laterally on 65 curves.
- When a car equipped with a car coupler constructed in accordance with my invention passes around a curve in the track, not only does the coupler stem 2 swing laterally 70 from its centralized position, but the coupler head 1 also usually turns upon the pivot pin 3. The results of the laterally swinging movements of the coupler stem and pivoted coupler head may, however, be separately 75 described. The rotation of the coupler head 1 upon the pivot pin 3 causes the centering slide or frame 5 to slide rearwardly upon the coupler stem 2 and effect a compression of the spring 6. Thereafter when the force 80 causing the displacement of the coupler head from its normal position ceases to act, the spring 6 expands, thereby causing the centering slide 5 to return to normal position and rotate the coupler head 1 to normal position with respect to the coupler stem. The operation of the mechanism for centering the coupler stem 2 with respect to the car body is as follows: When the coupler stem 85 swings laterally from its position in the longitudinal axis of the car it moves one of the spring seats 7 toward the other spring seat, which latter is held against retreat by bearing at its outer end against a stationary part 10 of the car. The approach of the 90 spring seats causes a compression of the springs 9 corresponding to the extent of lateral displacement of the coupler stem. Immediately upon a cessation of the force 95 causing the lateral swinging of the coupler from its normal position the springs 9 expand and the spring seat 7 which has been 100 displaced by the movement of the coupler stem is restored to normal position carrying with it the coupler stem so that the latter is 105 returned to a central position.
- It will be appreciated by those skilled in the art that mechanism constructed in accordance with my invention is compact and easily and economically applied, and is suitable for very heavy service. 110
- I claim:—
1. In a car coupler, the combination with a coupler head, of a coupler stem having openings through its opposite sides, a plurality of spring seats mounted upon said stem and adapted to project outwardly through said openings and to reciprocate transversely of said stem, and a plurality of transversely extending springs interposed between said 115 spring seats and yieldingly separating the same, the axes of said springs being spaced horizontally.
  2. In a car coupler, the combination with a laterally swinging coupler stem, of a plurality of springs movable with said stem and compressible upon a lateral movement of said stem to either side of its central position.

- tion, and spring seats reciprocatingly mounted upon and adapted to project outwardly beyond the sides of said stem, said spring seats being yieldingly separated by said springs, 5 the outer end faces of said spring seats being of convex form, and the axes of said springs being disposed in horizontally spaced relation on opposite sides of the apexes of said convex end faces.
- 10 3. In a car coupler, the combination with a laterally swinging coupler stem having openings through its opposite sides, of a plurality of spring seats movably mounted upon said stem and adapted to project outwardly through said openings, and a plurality of horizontally spaced springs movable with said stem and interposed between said spring seats, each of said spring seats being provided with means for maintaining 15 said springs in spaced relation.
- 20 4. In a car coupler, the combination with
- a laterally swinging coupler stem, of a plurality of parallel arranged horizontally spaced springs movable with said stem and compressible upon a lateral movement of 25 said stem to either side of its central position, and spring seats reciprocatingly mounted upon and adapted to project outwardly beyond the sides of said stem, said spring seats being yieldingly separated by said 30 springs and each being provided with a portion extending between said springs, and each of said spring seats also being formed at its outer end with a convex exterior face extending on opposite sides of the said portion of the spring seat which extends between said springs, said springs being disposed upon opposite sides of the apexes of 35 said convex faces.

In testimony whereof I affix my signature. 40

WILLIAM McCONWAY, JR.
